UNITED STATES PATENT OFFICE

EDGARD FRANKIGNOUL, OF BRUSSELS, BELGIUM, ASSIGNOR TO COMPAGNIE INTERNATIONALE DES PIEUX ARMES FRANKIGNOUL, SOCIETE ANONYME, OF LIEGE, BELGIUM

METHOD AND DEVICE FOR THE PRODUCTION OF PILES OF CONCRETE AND THE LIKE

Original application filed November 15, 1927, Serial No. 233,445, and in Belgium November 30, 1926. Divided and this application filed October 6, 1931, Serial No. 567,170.

The present invention relates to a method and device for enabling rapid and economical production of piles of concrete or of similar materials which are completely compressed or rammed along the whole length of the pile, and is a divisional application of my principal application No. 233,445 filed in U. S. A. on November 15, 1927.

According to said principal application the lining or tubing is provided, when driving the system into the ground, with the necessary equipment for concreting, that is to say the rammer. After concreting the rammer and the lining are alternately raised by fractions of the height of the pile which is being constructed. The lining is raised whilst the rammer, which was previously raised, carries out its ramming face.

The rammer, after sinking the lining, may serve for forcing into the ground the closing device for the lining or the point of sinking, and for sinking the lining by pressing the upper portion of the rammer, which forms an anvil, upon the upper portion of the lining upon which it rests. The rammer is actuated by a steam or compressed air hammer or by a simple fall.

After concreting, the space left free in the lining under the rammer after each raising of the latter is filled automatically with concrete obtained from a reserve formed in the lining itself.

According to the present invention this reserve is formed by using only the space which is left free in the interior of the body of the rammer, whilst according to the principal application said reserve is formed by utilizing the space left free between the lining and the body of the rammer concurrently with a space left free in the interior of the body of the rammer.

The concrete is introduced into the reserve by a mouthpiece provided at the upper end of the tube or lining.

The invention provides that the raising of the rammer is effected in such a manner that it is possible to allow the monkey to strike upon its upper end or anvil when it is raised in such a manner as to cause the mass of concrete contained in the reserve to be shaken,

this mass in some cases being too compact in order to allow it to flow.

For effecting the disaggregation of the concrete enclosed and to accelerate its descent during the raising of the rammer there is provided a member which is connected in the lining and pressing out the concrete when the rammer is raised. 55

The accompanying drawings illustrate by way of example, and not by way of limitation, various forms of construction of the invention. There are shown various modifications of carrying out the invention. 60

In these drawings:

Figures 1 to 5 illustrate diagrammatically various phases in the production of a pile. 65

Figure 6 shows a construction of the device in accordance with the invention.

Figure 7 is a section on the line VII—VII of Figure 6. 70

Figure 8 shows a modification of construction of the device shown in Figure 6.

Figure 1 shows the position of the parts at the moment when the sinking into the ground is to commence. 75

The tube 1 bears on the point 2. On this rests the rammer 4 of which the upper part is connected to an anvil 3 adapted to receive the blows from a monkey, arranged above this and illustrated diagrammatically at (5). 80 This anvil rests on the upper end of the tube 1. The monkey is, for example, a steam or compressed air actuated monkey or is simply a monkey having a free fall.

The point 2, the tube 1 and the column or rammer 4 are sunk simultaneously in such a manner as to occupy the position illustrated in Figure 2. Concrete is then introduced by the mouth 6 of the tube 1 into the space forming the reserve and formed by the annular space 19 contained between the tube 1 and the column forming the rammer 4. For the purpose of ramming, the rammer is raised to a height which may vary for example from 50 cms. to 2 meters. The concrete is then supplied so as to occupy the complete section of the tube 1 and for the whole height under the rammer. 85 90 95

Figure 3 illustrates this phase of the operation. The parts being in this position, the 100

monkey 5 is operated in such a manner as to produce the downward movement of the column forming the rammer 4 by reason of the blows from the monkey which it receives. The ramming of the concrete situated below this column is thus effected.

At the same time as the operation of ramming proceeds, the tube 1 is little by little extracted from the ground by means of a winch. The top of the tube gradually approaches the anvil 3 which is subjected to a downward movement under the action of the monkey.

Figure 4 shows this phase of the operation.

Soon the column 4 and the tube 1 assume a position relatively near that which they occupy in the case of Figure 2 after sinking; the operation of the monkey is then stopped temporarily as also the movement of the tube 1. The column forming the rammer 4 as also the anvil 3 and the monkey 5 which are connected together are then again raised in such a manner as to enable a fresh quantity of concrete to pass downwardly underneath the column-rammer 4.

It is possible when the column-rammer 4 has been raised to give a few strokes of the monkey so as to shake the system which is for the purpose of disaggregating the concrete in the annular space which is left free between the tube 1 and the column 4 and thus to produce its flow to the bottom of the tube 1 under the rammer 4.

The operation then continues as above described whilst simultaneously producing a downward movement of the column 4 under the action of the monkey and an upward movement of the tube 1 which thus meets the anvil of the column 4.

In the method of construction illustrated in the drawing the point 2 which may be of concrete is left in the ground.

As shown in Figures 6 and 7, the hollow column 4 formed as a tube, serves as a reservoir of concrete.

The lower portion of the hollow column forming a reservoir is provided with an opening, which is formed under a cap fitted on this column and provided with a hole of 50 which the section has a reduced portion 28. Said opening is arranged in such a manner that during ramming of the concrete this will not flow back into the interior of the ram, the concrete in the orifice forming a sufficiently compact closure.

This may be broken when lifting the ram by a flow of the monkey on the latter in such a manner as to produce the disaggregation of the mass of concrete contained in the ram, thus exposing the lower opening in the ram so as to allow a fresh charge of concrete to pass out.

At the upper end of the tube or lining 1 65 there is fitted a hopper 22 serving to conduct

the concrete into the interior of the column-ram 4.

This hopper 22 is provided with a portion 23 engaging with the interior of the column 4 and closing a slot 24 provided along one of the sides of the column so as to permit of relative movements with the tube 1 in spite of the provision of the hopper 22.

This hopper also serves to support a member 25 of which the lower portion 29 is shaped as an elephant's paw and serves to discharge the concrete when the column 4 is raised relatively to the lining 1.

In the case of Figure 8, the reservoir formed in the interior of the column-ram 4 is supplied from a concrete reservoir formed above the anvil 3 by an extension 26 of the tube 1. This extension forms the mouthpiece into which the concrete is poured.

The anvil 3 is provided with an opening 27 35 for the passage of the concrete.

It will be understood that the relative length of the tube 1 and of the column 4 may be modified according to the circumstances in such a manner that when the anvil 3 secured to the column 4 bears upon the tube 1, the lower portion of the said column 4 may be either above the lower portion of the tube 1, or below or at the same level.

I declare that what I claim is:

1. Device for the driving and construction of piles of concrete and like materials moulded in the soil comprising a driving point, a hollow column whose lower end serves as a rammer and which is constricted interiorly near its bottom said column resting during the driving work with its lower end upon the driving point and furnished at its upper end with an anvil which receives the impact of a hammer, a tube which during the driving work engages with its lower end upon the driving point and is subjected at its top end to the action of the anvil, a space forming a storage space for concrete provided interiorly of the column forming the rammer, means serving for the introduction of concrete into the column and means for causing the falling of part of the concrete contained in the column underneath the rammer while the latter is being raised.

2. Device for the driving and construction of piles of concrete and like materials moulded in the soil comprising a driving point, a hollow column the lower part of which serves as a rammer and which is constricted interiorly near its bottom, the said column bearing during the driving work with its lower end upon the driving point and furnished at its top end with an anvil which receives the shock of a hammer, a shaft lining which during the driving work engages with its lower end on the driving point, and is subjected at its top end to the action of the anvil, a concrete storage space provided in the interior of the column constituting the rammer, a hop-

per for the introduction of concrete into said column, a mouth-piece of the said hopper passing through a longitudinal slot formed in the wall of the column constituting the rammer so as to allow relative movements 5 of said column and shaft lining and means for causing the concrete contained in the column to drop underneath the rammer during the rising of the latter.

10 3. Device for the driving and construction of piles of concrete and like materials moulded in the soil comprising a driving point, a hollow column the lower part of which serves as a rammer and which is constricted interiorly, near its bottom, the said column bearing 15 during the driving work with its lower end upon the driving point and furnished at its top end with an anvil which receives the shock of a hammer, a shaft lining which 20 during the driving work engages with its lower end on the driving point and is subjected at its top end to the action of the hammer, a storage space provided in the interior of the column forming the rammer, means for the introduction of concrete 25 into the column and a pusher adapted to said means and serving to force the concrete towards the bottom underneath the rammer when the column is raised with relation to the 30 shaft lining.

35 4. Device for the driving and construction of piles of concrete and like materials moulded in the soil comprising a driving point, a hollow column the lower part of which serves as a rammer and which is constricted interiorly, near its bottom, the said column bearing 40 during the driving work with its lower end upon the driving point and furnishing at its top end with an anvil which receives the shock of a hammer, a shaft lining which during the driving work engages with its lower end on the driving point and is subjected at its top end to the action of the hammer, a first concrete storage space provided around the hammer 45 in a tube extending above the anvil, a second concrete storage space provided in the column below the anvil and a central opening provided in the anvil for the passage of the concrete from said first storage space to 50 said second one during the rising and falling of the hammer.

In testimony whereof I affix my signature.
EDGARD FRANKIGNOUL.
